AUTOMATIC CUT-OFF DEVICE FOR FUEL OIL BURNERS

Filed April 22, 1926

UNITED STATES PATENT OFFICE.

DORR R. MARTIN, OF DETROIT, MICHIGAN.

AUTOMATIC CUT-OFF DEVICE FOR FUEL-OIL BURNERS.

Application filed April 22, 1926. Serial No. 103,832.

This invention relates to automatic cut off devices for fuel oil burners and the object of the invention is to provide a device for stopping flow of fuel should the burner fail to ignite.

This device is designed for use with the intermittent type of fuel oil burner in which the fire turns on and off intermittently and is usually controlled by a thermostat for this purpose.

Another object of the invention is to provide a trip device which makes the cut off device inoperative when the fuel oil burner ignites.

15 A further object of the invention is to provide a means operating on the time principle for stopping the supply of fuel oil to the burner, the said means being automatically disconnected from the operative position as soon as the oil is ignited.

20 Another object of the invention is to provide an electric motor and an air pump operated by the electric motor to supply oil to the burner, the air under pressure being utilized to actuate a means for breaking the circuit to the electric motor to stop the pump should the oil fail to ignite.

25 These objects and the several novel features of the invention are hereinafter more fully described and claimed and the preferred form of construction by which these objects are attained is shown in the accompanying drawings in which—

Fig. 1 is a section through an automatic cut off device embodying my invention.

Fig. 2 is a view of the electrically driven pump and circuit therefor.

The pump 1, shown in Fig. 2, is of the usual type having an air inlet pipe 2 and an air outlet pipe 3 through which air is discharged under pressure. The pump 1 is driven by an electric motor 4 which is provided with current through the two wires 5 and 6. Two switches 7 and 8 are provided 40 in the line 5 either one of which may be opened to break the motor circuit. The switch 7 is preferably controlled by a thermostat which controls the motor according to the temperature of the house being heated. The switch 8 is shown more particularly in Fig. 1 and is provided with a switch button 9 which in the position shown

in full lines in Fig. 1 is closed. The pressure line 3, as shown in Fig. 1, leads to a nozzle 10 extending through the furnace wall 11 and through which a fuel oil and air mixture is sprayed into the interior of the furnace the fuel oil being fed to the mixing nozzle 10 through the pipe 40. A pipe 12 leads from the pipe 3 to the housing 13 shown in Fig. 1 and a member 14 is provided having a very small aperture therethrough through which air under pressure may flow very slowly. An annularly corrugated sheet metal expanding element 15 is provided in the housing 13 into which the air under pressure is adapted to pass from the member 14 and this member 15 is closed at the end by a member 16 having a stem 17 passing through an apertured bracket 18 formed integrally with the housing 13. A coiled spring 19 is positioned between the stationary member 18 and the movable member 16 and a link 20 is pivotally connected to the stem 17. A second link 21 is pivotally connected at one end to the link 20 and at the opposite end to the actuating member 22 which also extends through an aperture in the stationary bracket 18. The actuating member 22 is provided with an enlarged end 23 adapted to engage the switch button 9.

When the pump starts operating the air under pressure flows through the nozzle 10 where it is mixed with oil and discharged into the furnace 11 and the air under pressure also flows slowly through the small aperture in the member 14 into the longitudinally expandible element 15 which moves the stem 17 to the left of Fig. 1 thus causing the actuating member 22 to engage the switch button 9 and force it to the dotted position shown in Fig. 1 thus breaking the circuit to the motor and stopping the pump. This is a safety device for preventing flooding of the furnace with oil if the oil fails to ignite. Supported on the wall of the furnace is a casing 24 into which a gas pipe 25 leads and the gas pipe is provided with a jet 26 of porcelain, clay or lava to prevent deterioration and this jet throws a flame toward the oil and air jet 10 for igniting the oil when it begins to flow from the jet 10. A re-lighting plug 27 is provided in the side of the casing 24 which

may be removed for re-lighting the gas pilot should it ever go out. An air inlet opening 28 which is open to atmosphere is provided in the side of the casing 24 opposite the plug 27 and a bracket 29 is secured to the casing 24 and supports a bulb 30 in the air inlet opening 28. This bulb 30 is connected by means of a tube 31 with the interior of a vertically expandible element 32 having a plunger 33 at the upper end thereof extending through an opening provided therefor in the stationary bracket 18. The upper end of the plunger 33 normally lies flush with the surface of the bracket 18. The expandible element 32, tube 31 and bulb 30 are filled with a volatile fluid such as ether which is quickly expandible under influence of heat. The gas pilot which remains lighted all the time draws air to support combustion through the air inlet 28 and thus maintains the bulb 30 in a cool condition. The switch 8 normally remains in the closed position as shown in Fig. 1 during normal operation of the furnace and is only moved to the off position by the actuator 22 when the oil fails to ignite. With the switch 8 closed or on the "on" position the device is ready for operation. Assuming that the switch 7 shown in Fig. 30 2 is closed by a thermostat the motor 4 is driven and drives the pump 1 which feeds air under pressure through the pipe line 3 and through the jet 10. At the same time the air under pressure passes through the pipe 12 and very slowly through the small aperture in the member 14 to fill the expandible element 15. At the same time the gas flame from the jet 26 ignites the oil passing from the jet 10 which produces a puff at the instant of ignition tending to blow the heat produced by the pilot or the flame itself backward through the chamber 24 and air inlet 28 and about the bulb 30. This puff immediately expands the volatile fluid in the bulb and member 32 forcing the plunger 33 upwardly and moving the link consisting of the parts 20 and 21 to the position shown in dotted lines in Fig. 1 which prevents the actuator 22 from engaging the switch button 9 and allows the furnace to operate in the normal manner. When the thermostat again opens the switch 7 the pump is stopped which reduces the pressure in the expandible element 15 and allows the spring 19 to move the plunger 16 to the right of Fig. 1 until the links 20 and 21 are turned to the position shown in full lines in Fig. 1 and straightened out at which time the device is again ready for succeeding operations. In case the oil does not ignite no puff of flame is produced about the bulb 30 and therefore the plunger 33 does not move the links out of alignment and as the pressure is built up in the expandible element 15 the actuator

22 is moved to the left of Fig. 1 thus moving the switch button 9 to the dotted position and opening the switch 8 to break the motor circuit and stop the motor and pump thus preventing further fuel from passing into the furnace. When this has happened and the parts are returned to the normal position shown in full lines in Fig. 1 the operator pushes the button 9 to the position shown in full lines in Fig. 1 at which time the burner is again ready for operation. 70

In the construction of the device herein described an air pressure of approximately four pounds was provided discharging through the pipe 12 and the restricted orifice 14 was formed by a No. 80 drill. The plunger 17 has a movement of about three-sixteenths of an inch to engage the switch button 9 while the plunger 33 has a movement of about three thirty-seconds of an inch to break the toggle formed by the links 20 and 21. The size of the bellows member 15 is such that the air pressure multiplied by the cross sectional area is in excess of the pressure required to operate the push button 9. The size of the bellows 32, the conduit, 31 or pump 30, is not material but only a small quantity of ether should be employed in the bulb as too great a volume would produce too great a pressure and the pressure required to operate the plunger 33 is only that required to lift the links of the toggle which are simply two small brass bars. The size of the orifice 28 in the pilot flame casing needs to be sufficiently great to permit free flow of gases about the bulb 30 which is thin walled in order to permit rapid transfer of heat to the ether. The pilot flame should be merely of medium size, too large size flame usually being too great in pressure and therefore tending to prevent the "blow back" upon ignition of the oil in the furnace and too small a pilot flame tending to blow out. This flame may be regulated by a valve not here shown in the conduit 25 to secure the desired result. With a medium flame the pressure developed upon ignition tends to cause an instantaneous flicker of the flame to about the bulb and then a return to the position shown in the drawing. 100

It is to be understood, however, that the invention is not restricted to the specific sizes given as the only materially important factor is to provide a pressure in the bellows 15 sufficient in respect to its cross sectional area to exceed the pressure required to actuate the switch button and that this pressure shall build up slowly through a sufficient time period subsequent to operation of the electrically controlled means to permit ignition to take place as hereinbefore described. 110

From the foregoing description it becomes evident that the device is very simple and 130

efficient in operation, will not easily get out of order, will prevent flooding of the furnace with oil and provides a device which accomplishes the objects described.

5. Having thus fully described my invention, its utility and mode of operation, what I claim and desire to secure by Letters Patent of the United States is—

1. The combination with a furnace, of a fuel oil burner having a fuel nozzle discharging into the furnace, electrically controlled means for discharging oil through the said nozzle, a switch in the circuit for the said electrically controlled means, a pressure actuated device caused to operate upon operation of the electrically controlled means to discharge the oil into the furnace, the said pressure actuated device being arranged to open the switch at a certain time period subsequent to discharge of oil into the furnace, a conduit open to the furnace, a pilot flame extending through the conduit and adapted to ignite the oil when discharged, a device sensitive to change in temperature positioned adjacent the pilot flame and when heated to a predetermined extent adapted to prevent switch actuation by the pressure actuated device, the arrangement providing that, upon normal operation of the device and ignition of the fuel by the pilot, the increase of pressure within the furnace at the time of ignition causes heat of the pilot flame to be forced backwardly through the conduit to influence the temperature sensitive device.

2. The combination with a furnace, of a fuel oil burner having a fuel nozzle discharging into the furnace, electrically controlled means for discharging oil through the nozzle, a switch in the circuit for the said electrically controlled means, a pressure actuated device caused to operate upon operation of the electrically controlled means, the said pressure actuated means being arranged to open the switch at a certain time period subsequent to discharge of oil into the furnace, a pilot flame adapted to ignite the oil being discharged from the nozzle, a conduit for the pilot flame open to air exteriorly of the furnace, the air normally flowing into the furnace through the conduit to supply oxygen to the pilot flame, a temperature sensitive device supported in the air inlet end of the said conduit and adapted upon application of heat to prevent actuation of the switch by the pressure actuated means, the arrangement being such that upon ignition of the oil heat is applied to the said temperature sensitive means.

3. An automatic cut off device for fuel oil burners comprising a furnace, an oil nozzle opening into the furnace, means for supplying air under pressure to the nozzle, a pilot light adapted to light the oil as it discharges from the nozzle, an air inlet through which

air is adapted to be drawn to supply the pilot light, an expandible element having a bulb supported in the air inlet opening, the expandible element and bulb being filled with a volatile fluid, a second expandible element adapted to be slowly filled with the air under pressure, expansion of the said element by the air under pressure being adapted to actuate a switch, the arrangement being such that upon ignition of the oil the first named expandible element prevents the second element from actuating the switch.

4. An automatic cut-off device for fuel oil burners comprising the combination with a furnace, of an oil nozzle discharging into the furnace, means for supplying air to the nozzle to cause discharge of oil, an expandible element connected directly with the air supplying means and movable through the air pressure, electrical means for providing the air supply, a switch controlling the circuit therefor, said switch being positioned to be operated by the expandible element to break the circuit to the electrically controlled means, a temperature sensitive means to which heat is arranged to be supplied by pressure developed through ignition of the fuel supply, and means actuated by the temperature sensitive device to prevent operation of the switch by the expandible member.

5. An automatic cut-off device for fuel oil burners comprising the combination with a furnace, of a nozzle for discharging oil thereinto, an air pump for forcing air and oil under pressure through the nozzle, an electric motor for driving the pump, a circuit for the motor including a switch for making and breaking the same, an expandible element consisting of a bellows member having a stem movable by expansion or contraction of the bellows member, said stem including a jointed portion intermediate its ends, said switch being located in alignment with the stem whereby on expansion of the element and engagement of the stem with the switch the circuit is broken, and means influenced through ignition of the fuel in the furnace to move the jointed portion out of alignment with the remaining portions of the stem thereby permitting expansion of the bellows member without causing operation of the switch.

6. An automatic cut-off device for fuel oil burners comprising electrically controlled means for discharging oil and air into the furnace, a circuit for the said means, a switch in the circuit, an expandible element actuated by air pressure and operating in a predetermined time period to operate the switch and break the circuit, a pilot flame for ignition of the fuel including an enclosing casing having an opening to atmosphere and a conduit leading into the

furnace in proximity to the fuel injected therewith, a temperature sensitive element at the opening to atmosphere, the parts being so arranged that pressure developed in the

5 furnace on ignition of the fuel causes the pilot flame to blow back to the said opening to contact with the temperature sensitive

element under influence of heat to prevent operation of the switch by the pressure actuated device.

In testimony whereof I sign this specification.

DORR R. MARTIN.
